UNITED STATES PATENT OFFICE.

JAMES MARTIN FOX, OF MADISON, WISCONSIN.

RAILWAY SPIKE.

Application filed March 12, 1923. Serial No. 624,627.

To all whom it may concern:

Be it known that I, JAMES MARTIN FOX, a citizen of the United States, residing at Madison, in the county of Dane and State 5 of Wisconsin, have invented certain new and useful Improvements in Railway Spikes, of which the following is a specification.

The object of my invention is, to provide a railway spike differing in shape and construction from the standard railway spike now in general use for fastening rails; and one that will be much more effective and efficient in accomplishing the purpose for which it is intended; namely:

15 Holding the rails of a railway track securely from tipping or moving so as to get out of a safe position—thereby preventing derailments and accidents such as cause loss of life and damage to property.

20 The standard railway spike now in general use has four sides and four edges and after being in position for awhile in the ties to fasten the rails the sharp edges of the spike cut and gouge into the wood of the

25 ties which causes the holes to enlarge, thus allowing the spikes to become loosened; and, as a consequence, the spikes move, not only laterally but also vertically, thereby causing the spikes to become moved away from the 30 rails, creating a condition which causes a failure of the spikes to serve to help hold the rails in a safe and secure position.

My invention provides a railway spike with only two sides instead of four sides 35 and with only two edges instead of four edges and is so shaped that it cushions into the wood of the tie instead of cutting into it.

In my device simplicity, efficiency and durability are objects attained. With the foregoing and other objects in view the invention consists in the combination and arrangement of parts to be hereinafter fully described, pointed out in the appended claim and illustrated in the accompanying drawing which forms a part of this application 45 and in which—

Fig. 1 is a view of the spike in side elevation.

Fig. 2 is a view taken at right angles to 50 Fig. 1 including the aperture 8, for the reception of the auxiliary nail 2.

Fig. 3 is a view illustrating the application of my spiking device including the auxiliary nail 2.

Fig. 4 is a section taken on line A—A of 55 Fig. 1.

Like reference characters denote corresponding parts throughout the several views.

My spiking device comprises a principal 60 spike 1 and an auxiliary nail 2.

The spike 1, is formed with one flat inner side 3, with the oppositely disposed rounded outer side 4, with a pointed end 5 and with a cam-shaped head 6, provided 65 with the nose 7. The spike 1 is so driven into the tie that the nose 7 engages the base of the rail 9, the nail 2 rendering withdrawal or displacement of the spike from the rail base, a practical impossibility while 70 said nail is in position. The spike 1, is driven into the tie with its flat side 3 against the base of the rail thus permitting the head 6 to obtain a firm purchase upon the rail when 75 in position.

It will be readily understood that the shape and construction of the railway spike of my invention as described will be less liable to cause a cutting or gouging into the wood of the railway tie than the shape of 80 the standard railway spike now in general use which is four sided and four cornered.

What is claimed is:—

A railway spike comprising a head and a shank, the latter having a single plane face 85 for its inner side adapted to bear against the rail tread, and a single rounded face for its outer side tapering intermediate the extremities of the spike to the lower end thereof, said shank being provided with an aperture below the head of the spike extending transversely and downwardly from the outer to the inner face for the reception of 90 an auxiliary securing member.

In testimony whereof I affix my signature 95 in the presence of two witnesses.

JAMES MARTIN FOX.
